UNITED STATES PATENT OFFICE.

JACOB H. BECKMAN, OF SEATTLE, WASHINGTON.

DEVICE FOR CHARGING LIQUIDS WITH GASES.

1,183,794.

Specification of Letters Patent. Patented May 16, 1916.

Application filed February 8, 1915. Serial No. 6,691.

To all whom it may concern:

Be it known that I, JACOB H. BECKMAN, a citizen of the United States of America, and a resident of the city of Seattle, in the county of King and State of Washington, have invented certain new and useful Improvements in Devices for Charging Liquids with Gases, of which the following is a specification.

10 My invention relates to devices for charging liquids with gases and comprises certain novel parts and combinations of parts which will be hereinafter described and particularly pointed out in the claims.

15 The object of my device is to improve upon the devices of a similar character which are now in use, by freeing them from objections which now apply to the former devices; particularly to improve on such devices by preventing the stoppage of the pores in the walls of the chamber.

In the device, as herein shown, I have shown the form of construction which is now preferred by me.

25 Figure 1 is a longitudinal section through the chamber, or the chamber into which the gas is introduced, and through the pores in the walls of which it passes into the liquid being charged with gas. Fig. 2 is an end view of the lower end of this chamber. Fig. 3 is a section on line 3—3 of Fig. 1. Fig. 4 is a section on line 4—4 of Fig. 1. Fig. 5 is a sectional view through a cask or tank within which this device is shown in use.

30 In the course of manufacture or treating of various liquids, they are put through a process designed to charge them with a gas. The gas most commonly used is carbonic acid gas, in which case the process is a carbonating process. As this carbonating process is typical of all general classes, I will refer to such process as a carbonating process, although it is evident that the apparatus herein shown and the advantages obtained 40 thereby, will apply as well to charging liquids with other gases. As one of the liquids, which will be widely employed for this purpose, is beer, I will describe my process particularly in its application to the carbonating of beer, it being understood that the process is not limited to this particular product.

One form of apparatus which is used in carbonating beer, consists of a chamber, usually in the form of a cylinder, as the cylinder 45 of Fig. 1, which cylinder is composed of a

porous material through the pores of which gas may pass without excessive resistance. This cylinder is closed at the ends and immersed in the liquid being charged, a tube 60 being connected with one end of such cylinder, through which gas under a pressure, which in some cases may be very slight, is supplied to said cylinder. The gas gradually escaping through the pores of the cylinder is discharged into the beer, or other liquid, as a series of minute bubbles. The gas is thus brought into contact with the liquid in such manner as to secure the most effective results.

70 In using devices of this character, it has been found that, where, as is often the custom, the device is immersed within the liquid before the supply of gas thereto, the liquid passes from without into said cylinder, the 75 walls of which act as a filter and retains within its pores whatever of solid or gummy matter may be contained in the solution, whether this be simply suspended therein or more nearly in the form of a solution. By 80 reason of this fact the pores of the wall become clogged, thus reducing the rate of passage of the gas therethrough, and in some cases necessitating much higher pressure in the gas. In addition to this, if the chamber 85 is filled with liquid, this liquid must be expelled before the normal gaseous conducting capacity has been restored, and as the flow of liquid through such porous material is relatively slow, it is some time before the 90 device can work to its proper normal capacity.

To avoid the above difficulties, I have provided the chamber with a port or ports, forming passages for the ingress and egress 95 of liquids. These ports are preferably located at the extreme lower part of the chamber and a valve, or valves, provided which may close said ports against outward flow of the gas, but which will be maintained 100 open until the liquid, which may have entered the chamber, has been expelled.

105 Referring to the drawings, Fig. 1 represents a section of a tube which is formed of porous material, such for instance, as unglazed earthen ware, through the pores of which gas may pass from the chamber into the liquid, into which it is immersed. The particular shape of chamber shown lends itself best for the particular use for which it is intended, although, except as a matter of convenience in use, the shape is not essen-

tial. One end of this chamber, that which ordinarily would be the uppermost one in use, is closed by a cap 2. The tightness of the joint between the cap and cylinder may be secured by a packing ring 20, or in any other convenient manner. In the construction herein shown, the two parts are simply clamped together by force exerted axially of the chamber. The cap 2 is provided with 10 one or more ports 21, which connect the channel contained in the stem 22 with the interior of the chamber. This stem, or nipple 22, is provided with means by which a hose may be readily secured thereto. Such 15 hose connects the chamber with the source of supply of gas.

The other head 3 is similarly secured to the end of the cylinder 1 and is provided with one or more ports 31, through which 20 liquid may pass between the exterior and interior of the chamber. This cap is provided with a central hole, through which passes a rod 4 which is screw-threaded or otherwise secured in the cap 2, and which 25 has the end, which projects beyond the cap 3, threaded to receive a clamping nut 40. Preferably, the walls surrounding the ports 31, which are intended to serve as valve seats, extend inward from the inner seat 30 of the cap so as to form ring shaped valve seats, against which the floatable valve 5 may seat.

The valve 5 is made of any material found suitable for this purpose. It should 35 have sufficient flotation so that it will rise when the liquid is admitted to the chamber and fall as the liquid falls, so as to eventually be seated upon the valve seats surrounding the ports 31. This valve, in 40 the construction shown, has a central hole through which the clamping rod 4 passes. The fit of the valve about this rod and also within the cylinder 1 should be sufficiently loose that its movements will not be hampered by friction.

When this device is inserted within a liquid, the first result is that the liquid enters through the ports 31 and fills the chamber. It remains in this condition until gas 50 has been admitted of sufficient pressure to expel the liquid. As the ports 31 are at this time freely open, it requires but slight pressure to expel the liquid. As soon as the liquid has been expelled, the valve seats 55 upon the margins of the ports and thereafter the gas escapes through the pores of the walls.

In using this construction there is no tendency to clog the pores of the walls with 60 sediment, and therefore, the device may begin working at its full capacity immediately after the gas pressure has been turned on. As ports are provided through which liquid may freely enter the chamber, and 65 may be as freely expelled, it is not neces-

sary to close the pores in the walls of the chamber, as long as it could be closed, the liquid ports and the valve not closed, as herein shown.

While I have shown the form of construction which is preferred by me, it is evident that this form may be widely varied without essentially altering the principle of the device.

Having thus described my invention, what I claim as new, and desire to secure by Letters Patent of the United States of America, is:—

1. A gas charging device for liquids comprising a porous-walled chamber having a gas supply connection and a liquid-passing port, a floatable valve within said chamber and adapted to close said port when the liquid has been discharged from the chamber.

2. A gas charging device for liquids comprising a porous-walled chamber provided with a gas supply connection at its upper part and a liquid-passing port in its lower surface, a floatable valve within said chamber adapted to engage and close said port as the liquid level within the chamber is lowered.

3. A gas charging device for liquids comprising a porous-walled chamber having a gas supply connection and a liquid-passing port located in the lower part thereof, a floatable valve in said chamber and means for guiding said valve into position to rest upon and close said port as the liquid level falls in the chamber.

4. A gas charging device for liquids comprising a chamber having porous walls and a liquid-passing port in its lower part, a gas supply connection with said chamber, a valve adapted to be actuated to close said port by the lowering of the level of liquid within said chamber.

5. A gas charging device for liquids comprising a porous walled chamber having a gas supply connection and a liquid-passing port freely opening for the inward passage of liquid, and a valve adapted to close said port against outward flow of gas, said valve being controlled by the level of liquid within said chamber.

6. A gas charging device for liquids comprising a chamber having porous walls and provided with gas supply connections and having a liquid-passing port at its lower part, a floatable valve within said chamber and a bar for guiding said valve into position for closing said port as the valve is lowered by lowering of the liquid level within the chamber.

7. A gas charging device for liquids comprising a porous-walled chamber having gas supply connections and a liquid-passing port located at its lower part and having elevated

narrow seats, a floatable valve within said chamber, and means for guiding said valve into position upon said seats when the liquid level within the chamber is lowered through the expulsion of the liquid by the gas.

8. A gas charging device for liquids comprising a porous walled chamber having a gas supply connection, a liquid port opening at the lower part of said chamber and an inwardly opening valve controlling said port, and means controlled by the liquid level within the chamber for controlling the position of said valve.

9. A gas charging device for liquids comprising a porous walled cylinder, a cap for one end of said cylinder having exterior means for attachment of a gas supply pipe and ports communicating from said pipe

connection with its interior, a cap for the other end of said cylinder having a hole for the passage of a clamping rod and liquid-passing ports, a clamping rod secured to the first named head and passing through the hole in the other head, a clamping member engaging the projecting end of said rod and the head, and a floatable valve within the cylinder and adapted to close the liquid-passing ports when lowered thereto by the expulsion of the liquid from said cylinder.

Signed at Los Angeles, Cali., this 29th day of January, 1915.

JACOB H. BECKMAN.
